Shinji Takashima, Kanagawa, Japan, assignor to Miyata Industry Co., Ltd., Chigasaki City, Kanagawa, Japan, a corporation of Japan

Filed May 1, 1969, Ser. No. 16,978

Claims priority, application Japan Nov. 11, 1968

Term of patent 14 years

Int. Cl. D12—11

U.S. Cl. D90—8

FIG. 1

FIG. 2

FIG. 3

FIG. 4

FIG. 5

FIG. 1 is a right side view of a frame for bicycle showing my new design,

FIG. 2 is a top plan view thereof,

FIG. 3 is a front view thereof,

FIG. 4 is a rear view thereof, and

FIG. 5 is a top and right side perspective view thereof.

The elements of a bicycle, shown in broken lines in FIG. 5, are included for illustrative purposes only.

I claim:

The ornamental design for a frame for bicycle, as shown and described.
